UNITED STATES PATENT OFFICE

WILLIAM B. SHAFER, OF PITTSBURGH, PENNSYLVANIA, ASSIGNOR TO PITTSBURGH ASPHALT VAULT COMPANY, A CORPORATION OF PENNSYLVANIA

HINGE MECHANISM FOR GRAVE VAULTS

Application filed July 23, 1928. Serial No. 294,883.

My invention relates to hinge mechanisms for grave vaults and particularly to hinge mechanisms for grave vaults of the concrete or asphalt type.

- 5 An object of my invention is to provide a simple and effective hinge mechanism for grave vaults having a separate cover whereby the latter may be accurately lowered to its closed position.
- 10 A further object of my invention is to provide a hinge mechanism for grave vaults that may be detachably connected thereto for temporary operation and removed therefrom.
- 15 A still further object of my invention is to provide a hinge mechanism for grave vaults that may be detachably connected to, and removed from, the vault for successive operations.
- 20 Grave vaults of asphalt or concrete or a combination of these materials are usually constructed in two parts, a main body portion and a cover for closing the vault and that is sealed in its closed position. It is 70 advisable that the cover be accurately located in its closed position when the vault is to be sealed in the grave. It is impractical to provide permanent hinges for this purpose by reason of the fact that it is desired to avoid insofar as possible the use of metal penetrating the surfaces of the vault in the construction of such devices and hinges that are sufficiently strong to support and secure the registration of the cover would add materially to the cost of the vault.

In accordance with the present invention, I provide hinge mechanism that is of sufficient mechanical strength to support the cover in its raised position and which operates to insure that the cover may be accurately lowered to its final closed position for sealing. The hinge mechanisms are arranged to be detachably connected to the body portion of the vault in such manner 45 that the weight of the cover may be supported thereby. The hinge mechanisms are also arranged to firmly engage the cover whereby the weight of the latter may be supported by the hinge mechanisms and the position 50 of the cover may also be controlled by means

of ropes or cables connected to the hinge mechanisms.

The details of construction and operation of my invention will be described in connection with the accompanying drawing, in 55

Figure 1 is a view in side elevation of a grave vault provided with hinge mechanisms constructed in accordance with my invention;

Fig. 2 is a view in transverse vertical section taken on line II—II of Fig. 1;

Fig. 3 is a fragmentary view in top elevation of a portion of the structure of Fig. 1;

Fig. 4 is an elevational view of one member 65 of the hinge mechanism; and

Fig. 5 is an edge view of the member of Fig. 4.

A grave vault 1 that is adapted to co-operate with the hinge mechanism of my invention comprises a main body portion 2 which may be constructed, for example, of an outer portion of concrete 3 and an inner lining of asphalt mastic 4. The vault 1 comprises a cover 5 having recessed portions 6 75 that are adapted to receive the inclined edges 7 of the main body portion 3.

The rear wall of the vault 1 is provided with two pairs of bolts 8 which may be anchored in the concrete wall in any suitable 80 manner, such, for example, as by nuts 9 and a strap 10 for insuring the proper vertical spacing of the bolts. The outer ends of the bolts 8 are provided with heads 12.

The cover 5 is adapted to be secured to the 85 main body portion 3 by means of a hinge mechanism comprising two hinge bars or leaves 13 and 14. The bar 13 that is adapted to be secured to the main body portion is provided with two keyhole slots 15, the larger portion of which is adapted to pass over the heads 12 of the bolts 8 and the smaller portion of which is adapted to receive the bolt 8.

The other bar or leaf 14 is adapted to be secured to the cover 5 by means of two clips 90 16 that are of substantially L-shape, each being provided with a hook portion 17 for engaging the lower edge of the cover 5 on the front and rear, respectively, of the latter. Each of the clips 16 is provided with a stud 100

bolt 18 that is adapted to be received by a corresponding hole 19 in the top leaf or bar 14. The bar 14 may be securely fastened to the clip 16 by wing nuts 20, each having a ring 21 to which a rope or cable may be secured. The bars or leaves 13 and 14 are connected by a pin 22.

The bars 13 and 14 are hinged substantially at the upper corner of the cover whereby the latter will not require additional width of the grave in its open position.

In the employment of a vault utilizing hinge mechanisms of my invention, the cover may be placed upon the vault before the latter is lowered into the grave. The hinge mechanisms are then placed in position by passing the large portions of the slots 15 in the bars 13 over the heads 12 of the bolts 8 and forcing the bars 14 downward until the bolts 8 occupy the narrow portions of the slots. The clips 16 are then placed over the edges of the cover 5 and the bar 14 is securely fastened thereto by the wing nuts 20. The vault with the cover in closed position is next lowered. The cover may then be raised to its open position by suitable ropes connected to certain of the rings 21 and retained by a pin or other device in the grave wall until the vault has received its contents.

When it is desired to close the vault, the cover is lowered by ropes or other suitable means connected to the wing nuts 20 and the hinge mechanisms insure that the cover will return to the position from which it was raised. Sealing material will have been previously applied to the edges of the vault in order that the cover may be hermetically sealed in position.

In order to remove the hinges for subsequent use on another vault, the wing nuts 20 are removed and the bar 14 is raised to permit the removal of the clips 16. The bar 13 is then disconnected by pulling it upward until the bolts 8 are in the large portions of the slots 15, whereupon the bar is slipped over the heads of the bolts 8 and the mechanism is removed.

From the foregoing, it will be appreciated that I have provided a hinge mechanism that may be detachably secured to a vault and the cover therefor while the latter is in closed position. The cover may then be raised and lowered again with the assurance that it will return to its proper closed position for sealing the vault. The hinge mechanisms may be easily and quickly removed from the vault and employed in a subsequent operation in the same manner.

The above-described advantages of construction and operation will be apparent to those skilled in the art to which my invention relates. My invention may be variously embodied. For example, it may be proposed to fasten the upper hinge bar directly to the cover by stud bolts embedded therein instead

of being carried by clips. My invention is, therefore, not to be limited except as expressed in the claims.

I claim as my invention:

1. The combination with a vault having two separable portions, of a hinge mechanism comprising a member adapted to be detachably connected to the exterior of one of said portions and readily removable therefrom and a second member adapted to be securely fastened to but detachable from the exterior of the other portion whereby the latter may be supported by said second member and whereby the hinge mechanism may be removed when the vault is in assembled position. 70

2. The combination with a vault having a body portion and a cover therefor, said body portion having a plurality of outwardly extending headed projections, of a hinge mechanism on the exterior of said vault for connecting said cover to said body portion and comprising a slotted bar for detachable connection to said projections, a bar hinged to the first bar, two clips for engaging opposite exterior edges of said cover and bolts for detachably securing said clips to the second bar whereby the entire hinge mechanism may be removed when the cover is in closed position. 75

3. The combination with a vault having a main body portion and a cover portion therefor, of a hinge mechanism for connecting said cover to said body portion comprising two clips for engaging the exterior of one of said portions, a member adapted to be connected to said clips and a second member hinged to the first member and adapted to be detachably connected to the exterior of the other of said vault portions, whereby the hinge mechanism may be connected to and disconnected from said vault when the cover is in closed position. 80

4. The combination with a vault having two parts comprising a main body portion and a cover, of a hinge mechanism for said vault comprising a member detachably connected to, but readily removable from, the exterior of the main body portion, a second member hinged to the first member and having openings therein, and means comprising stud bolts connected to exterior of said cover for detachably connecting the latter to said second member whereby the hinge mechanism may be removed from the vault when the cover is in closed position. 85

5. The combination with a grave vault comprising a main body portion and a cover, of a hinge mechanism for temporarily connecting said cover to said main body portion comprising a slotted member adapted to detachably engage a projection on the exterior of said body portion, a pair of clips for detachably engaging the exterior of said cover, a second member hinged to said slotted mem- 90

ber, and means for connecting the second member to said clips, whereby the hinge mechanism may be connected to and removed from the vault when the cover is in its closed position.

6. The combination with a grave vault comprising a main body portion and a cover, of a hinge mechanism for temporarily connecting said cover to said main body portion comprising members having keyhole slots therein for engaging projections on the exterior of said main body portion, members hinged to the slotted members, and means for detachably connecting the hinged members to the exterior of said cover whereby the entire hinge mechanism may be readily removed when the cover is in its closed position.

In testimony whereof, I have hereunto subscribed my name this 20th day of July, 1928.

20 WILLIAM B. SHAFFER.
